UNITED STATES PATENT OFFICE.

OSCAR O. NYGAARD, OF SAUGUS, MASSACHUSETTS, ASSIGNOR TO COMBUSTION ENGINEERING CORPORATION, OF NEW YORK, N. Y., A CORPORATION OF NEW YORK.

STOKER AIR CONTROL.

Application filed July 31, 1925. Serial No. 47,265.

My present invention relates to stokers, and more particularly to an improved apparatus for distributing and regulating the flow of air to the fuel bed in automatic 5 stokers.

In stoking apparatus, and particularly automatic stoking apparatus of the types in use at the present day, and with the type of fuel necessarily employed therewith it 10 becomes essential for a proper economical working of the apparatus to provide oxygen containing fluid, such as air, to the fuel bed in proportion to the depth of the fuel in the bed at any point throughout the length 15 thereof, and, in the past, although many attempts have been made to devise means for regulating the amount of air in the fuel bed, all such devices have failed to function properly as they operated over too great 20 an area of the stoker. The tendency in automatic stokers is for the units to become larger and larger as time goes on with the result that the difference in the thickness of the fuel bed on the grate at the receiving 25 or inlet end and at the dumping or exit end is continually increasing.

In my copending application, Serial No. 627,065, filed March 23, 1923, I have described and claimed an improved apparatus 30 for regulating the flow of air to the fuel bed in automatic stokers and the present application is to be considered as a continuation in part of such application, the form of apparatus herein described and claimed having 35 been disclosed in said copending application. The form of apparatus for enabling me to regulate the flow of air through the fuel bed at any point or at a plurality of points along the length thereof is that disclosed in Figs. 5-8 of such copending application, this form utilizing but a single form of tuyère forming block, the means for regulating the amount of air passing through the tuyères being located on a separate means 40 carried by the sides of the fuel trough and acting as a support for the tuyère blocks.

The object of my invention, therefore, is an improved apparatus for regulating the flow of air through a plurality of superimposed tuyère forming blocks and into a fuel bed.

In the accompanying drawings illustrating the preferred embodiment of my invention,

Fig. 1 is a sectional side elevation through 55 a row of tuyères showing my invention associated therewith;

Fig. 2 is a vertical sectional elevation on the line 2-2 of Fig. 1;

Fig. 3 is a front elevation of the frame 60 members shown in Fig. 1;

Fig. 4 is a vertical sectional side elevation of the tuyère forming block employed in this modification of my invention;

Fig. 5 is a fragmentary plan view of the 65 tuyère forming block shown in Fig. 4, and

Fig. 6 is a sectional elevation on the line 6-6 of Fig. 1.

Referring to the drawings, 10 designates the foundation on which is mounted the 70 spaced fuel troughs 11 constituting supports for the tuyère blocks, and 12 designates a portion of the brick masonry enclosing the stoker apparatus, a channel iron 13 extending across the furnace and acting as a support for the front ends of the fuel troughs 11, a plate 14 closing the space extending between the side walls 15 and the base 10 and channel iron 13.

Secured to the sides of the troughs 11 by bolts 16 is a frame 17 provided on the inner opposite faces with spaced projections 18 and spacing bars 19, the opposite projections 18 being in alignment, as clearly shown in Figs. 2 and 3. It will be noted 80 from an inspection of Fig. 3 that the various pairs of projections 18 differ in length, thus providing passages through the spaced frames 17 of different cross sectional area.

In my invention I utilize a tuyère forming 90 block of the form illustrated particularly in Figs. 4 and 5 and designated generally by the numeral 20, this block consisting essentially of a floor plate 21 provided on the face and on the forward side edges with 95 laterally projecting flanges 22, each flange being provided with a plurality of grooves 23 which, when the tuyère block 20 is in assembled position in the apparatus, form, with the grooves of the adjacent tuyère 100 blocks, orifices through which air from a wind or air chamber may flow. The space defined by the under surfaces of the troughs 11 and the rearward surface of the channel 13, plate 14, and the upper surface of the base 10 forms an air or wind box 24 which

receives air through a flue 25 provided with an adjustable damper 26 and by means of

which the air may be regulated. In assembling the form of tuyère block employed, the floor plate 21 is pushed into and through the space between the projections 18 and the 5 adjacent spacing bar 19 on the frame 17, the front ends of the floor plates being each provided with perforations 27 through which is passed a stud or bolt 28 which locks the tuyère block in position and 10 whereby each tuyère block may be independently removed and replaced.

While the cross sectional area of the space between tuyère blocks as defined by the 15 projections 18 is sufficient to properly proportion the amount of air passing through the tuyères and to any portion of the fuel bed 29 on said tuyères, and therefore no other means of regulating the flow of air from the wind box 24 is necessary, yet it 20 may sometimes happen that it is desirable to completely shut off the flow of air through the tuyère blocks or through any one bank of the same. In order to provide for this contingency I have utilized the form of damper 25 or shutter disclosed in the application of which this is a continuation in part, and have associated with each bank of tuyères a structure consisting of a plurality of generally downwardly extending levers 30 each pivotally secured to the side or wall of the trough 11 by bolt 31, and each of the levers 30 is provided with a longitudinally extending slot 32. Pivotally secured to the levers 30 by pins 33 is a rod or bar 34 and by means 35 of which the levers 30 may be operated simultaneously. Pivotally mounted in suitable bearings in the troughs 11 and extending transversely of the stoker is a shaft 35. Rotatably mounted on said shaft at intervals and extending upwardly therefrom are arms 36, each provided with a longitudinally extending slot 37 which fits over a pin 38 secured to, and extending laterally from, the rod or bar 34. Each member 36 may be 40 so arranged as to be operated independently and thus each member 36 may control simultaneously all of the levers 30 of a bank of levers. In place of the above, I may provide a means for operating all of the members 36 simultaneously and in this event each member 36 is rigidly attached to the shaft 35, while also attached to the shaft 35 and extending downwardly therefrom is a member 39 which has pivotally secured at its 45 lower end a forwardly extending operating rod 40 and by means of which the shaft 35 may be rocked. Secured to each of the levers 30 adjacent to the pivot bolt 31 is a damper plate 41, each plate covering the 50 space occupied by a plurality of tuyère blocks 20. It is possible, therefore, to shut off the flow of air from a wind box 24 to

any one of the fuel troughs 11 or to the entire bank of troughs 11 in a stoker.

While I have necessarily shown and described the preferred embodiment of my invention somewhat in detail, it is to be understood that I may vary the size, shape, and arrangement of parts within wide limits without departing from the spirit of the 65 invention.

Having thus described my invention, what I claim as new is:

1. In an automatic stoker, a fuel trough, an air channel at each side thereof, frames 75 on said fuel trough, tuyères arranged in stacked relation mounted on said frames, capping said channels, dampers for closing said air channels at will, each tuyère having a floor plate, and means located between 80 adjacent floor plates for determining the amount of air passing through each tuyère.

2. In an automatic stoker, a fuel trough, means to feed fuel into and out from said trough, an air channel at each side thereof, 85 dampers for closing said air channels at will, a frame on said trough, tuyères capping said air channels and connected to said frame, and means in the frame for determining the flow of air through each tuyère. 90

3. In an automatic stoker, a fuel trough, means to feed fuel into and out from said trough, an air channel at each side thereof, a frame on said trough, tuyères capping said 95 air channels and connected to said frame, and means in the frame for determining the flow of air through each tuyère.

4. In an automatic stoker, a pair of fuel troughs arranged parallel to and spaced apart from each other and defining by such spaced relation an air channel, frames secured to the opposing faces of the fuel troughs, tuyères arranged in stacked relation mounted on said frames and capping said channels, dampers for opening or closing 100 said air channels at will, each tuyère having a floor plate and means located between adjacent floor plates for determining the amount of air passing through each 105 tuyère. 110

5. In an automatic stoker, a fuel trough, an air channel at each side thereof, frames mounted on the margins of said trough, tuyère forming blocks arranged in stacked 115 relation mounted on said frames and capping said chambers, each of said blocks having a floor plate, dampers for closing said channels at will, and means located between adjacent floor plates for controlling the amount of air passing through the respective tuyères. 120

In testimony whereof, I have signed my name to this specification.

OSCAR O. NYGAARD.
